UNITED STATES PATENT OFFICE.

AXEL A. MONSON, OF CHICAGO, ILLINOIS.

STEERING MECHANISM.

Application filed October 11, 1923. Serial No. 668,008.

To all whom it may concern:

Be it known that I, AXEL A. MONSON, citizen of the United States, residing at Chicago, in the county of Cook and State of Illinois, have invented a certain new and useful Improvement in Steering Mechanism, of which the following is a full, clear, concise, and exact description.

My invention relates to mechanism for preventing the steering mechanism of automobiles or other vehicles from functioning to guard against theft.

In practicing my invention the steering wheel is locked against rotation by means of mechanism that preferably cooperates directly with the steering wheel shaft. A cap is disposed upon the upper end of the hollow steering column, the skirt of the cap surrounding said column. The mechanism for holding the steering wheel and shaft against rotation is disposed in the cap. A key controlled lock serves to place the holding mechanism in non-functioning position, the arrangement being such that the holding mechanism may be instantaneously adjusted to function, without aid of the key lock and merely by hand pressure upon one of the members of the holding mechanism.

The invention will be more fully explained by reference to the accompanying drawing in which Fig. 1 is an axial sectional view in the region of the steering wheel, illustrating the preferred embodiment of the invention; Fig. 2 is a view taken at right angles to the direction in which Fig. 1 is taken and showing the cap and steering shaft in elevation and the wheel in section; Fig. 3 is a sectional view on line 3—3 of Fig. 1; and Fig. 4 is a general view in elevation.

Like parts are indicated by similar characters of reference throughout the different figures.

The steering mechanism includes a steering shaft 1, a hollow column 2 surrounding the shaft, and a hand steering wheel in driving relation to the shaft. In the structure illustrated the steering wheel has a stub shaft 4 that is in gear connection with the main shaft 1. The hand wheel turns the shaft 1 by means of the pinion 5 upon stub shaft 4, the planetary pinions 6 and the stationary internal gear 7 upon and within the upper and enlarged end of the column 2. The planetary pinions are mounted on the upper end of shaft 1 in which the lower end of stub shaft 4 is also journaled.

The stub shaft 4 is provided with holding formations that are employed when the shaft 1 is to be held against rotation. These holding formations preferably reside in the teeth of the pinion 5 between which the inner end of plunger 8 is receivable to lock the wheel. This plunger is horizontally and radially disposed in a cap 9 that is screwed upon column 2 and is held in rigid assembly with said column by a coupling pin 10, which is carried by the cap and is in threaded engagement with the cap and column, between and along which elements the pin is disposed.

The plunger 8 is pressed upon outwardly by a spring 11 which bears at one end against the cap and at its other end against a holding formation upon the plunger 8, this holding formation being preferably in the form of a shoulder 12.

A plunger 13 is also carried by the cap, this plunger being beneath and angular to the plunger 8 and positioned to engage the outer flat face of the shoulder 12 when the plunger 8 has been pushed inwardly into one of the recesses 7 whereby the steering wheel and shaft are locked against rotation. A spring 14 serves to place the plunger 13 in holding engagement with the holding formation 12 of plunger 8.

A key controlled lock 15 has an eccentric pin 16 received in a slot 17 in the plunger 13. When the steering mechanism is to be unlocked, the lock barrel is turned to bodily turn the pin 16 to depress the plunger 13 against the action of spring 14. When plunger 13 has cleared the holding formation 12, the spring 11 will move the plunger 8 outwardly and out of engagement with the selected teeth of pinion 5. The holding formation 12 will come to rest in engagement with the top of plunger 13, whereby the lock need no longer be relied upon to hold the plunger 13 down. The relation of the parts is now such that the plunger 8, whose outer end is accessible for the purpose, may be pushed by hand into a selected inter-tooth space to lock the steering wheel and shaft, the key operated lock not requiring operation for this purpose.

The element 8—12 of the holding mechanism covers the pin 10 to guard against tampering.

I do not wish to be limited to the precise details of construction shown, as changes may readily be made without departing from the spirit of my invention, but having thus

described my invention, I claim as new and desire to secure by Letters Patent the following claims:

1. Steering mechanism including a steering shaft; a hollow column containing said shaft; a cap upon said column; mechanism in the cap for rigidly assembling it with the shaft to prevent the shaft from turning, said mechanism comprising an outwardly spring 5 pressed plunger engageable at its inner end with a holding formation with which the shaft is provided to prevent the shaft from turning and accessible at its outer end to be depressible toward the shaft, a second plunger 10 angular to the first plunger and spring pressed toward the first plunger and engageable with a holding formation, that is provided upon the first plunger, when the first plunger is in holding relation to the shaft; and a key controlled lock in adjusting relation to the second plunger to withdraw it out of holding engagement with the first plunger to break the holding relation of the latter with the shaft, the holding formation upon the first plunger being positioned, when this plunger is in its outer position, to hold the second plunger in its withdrawn position and ready for holding engagement with the holding formation 15 upon the first plunger when the latter is pushed into holding relation with the shaft.
2. A steering mechanism including a steering shaft; a hollow column containing said shaft; a cap upon said column; mechanism in the cap for rigidly assembling it with the shaft to prevent the shaft from turning, said mechanism comprising a

plunger engageable at its inner end with a holding formation with which the shaft is provided to prevent the shaft from turning 40 and accessible at its outer end to be depressible toward the shaft, a second plunger angular to the first plunger and engageable therewith to maintain it in holding relation with the shaft and a key controlled lock in 45 adjusting relation to the second plunger to withdraw it out of holding engagement with the first plunger to break the holding relation of the latter with the shaft, the first plunger being positioned, when this plunger 50 is in its outer position, to hold the second plunger in its withdrawn position.

3. A steering mechanism including a steering shaft; a hollow column containing said shaft; a cap upon said column; mechanism in the cap for rigidly assembling it with the shaft to prevent the shaft from turning; said mechanism comprising a plunger engageable at its inner end with a holding formation with which the shaft is provided to prevent the shaft from turning and accessible at its outer end to be depressible toward the shaft, a second plunger angular to the first plunger and serving to hold the first plunger in holding relation to the shaft and a key controlled lock in adjusting relation to the second plunger to withdraw it out of holding relation with the first plunger to break the holding relation of the latter with the shaft.

In witness whereof, I hereunto subscribe my name this eleventh day of September A. D., 1923.

AXEL A. MONSON.
